ROBERT F. BRACKE, OF CHICAGO, ILLINOIS, ASSIGNOR TO CURTIS B. CAMP, TRUSTEE,
OF GLENCOE, ILLINOIS

CARBURETOR

Application filed November 30, 1927. Serial No. 236,613.

My invention relates to improvements in carburetors and more particularly to the fuel lift type of carburetor.

An object of the invention is to provide 5 an improved carburetor.

A further object is to provide a carburetor which, under all normal operating, operates with maximum fuel economy, but in which, at or near wide open throttle position, a relatively greater quantity of fuel may be delivered to the induction passage.

A further object is to provide a carburetor in which the fuel economizer functions in such a way as not to reduce the efficiency of 15 the fuel lifting properties of the carburetor, but which actually increases these properties below three-quarters open throttle position.

A further object is to provide a carburetor which precludes the presence of too rich 20 a mixture in the induction chamber at less than three-quarters throttle position.

A further object is to provide a carburetor which eliminates the presence of gas or air bubbles in sufficient quantity in the fuel 25 chamber to impair the uniform flow of fuel to the primary intake or fuel nozzle, thus preventing the passage of the fuel from the fuel chamber in slugs separated by air pockets.

30 A further object is to provide a carburetor in which air bubbles collecting in the fuel chamber are continuously drawn into and commingled with the fuel stream passing therefrom so as to prevent the accumulation of relatively large quantities of air in the fuel chamber.

Other objects and advantages will be more particularly pointed out in the following specification and appended claims.

40 The carburetor is illustrated in the accompanying drawings forming a part of this application, in which.

Figure 1 is a sectional view of the carburetor and a fuel supply tank;

45 Figure 2, a view along the line 2-2 of Figure 1, and

Figure 3 is a fragmentary sectional view of a modified form of a part of the carburetor illustrated in Figure 1.

50 The invention will be explained as em-

bodied in that type of carburetor which I have fully illustrated and explained in my co-pending application for a patent on vacuum feed carburetors, Serial No. 155,598, filed December 18, 1926, and consists chiefly, 55 with reference now to the drawings, in an induction chamber 1, a secondary air inlet 2, and a delivery passage 3 having its mouth adapted for registration and connection with the intake manifold 4 of an internal combustion engine. The chamber 1 and the passage 3 constitute, and shall hereinafter be referred to as, "the induction passage of the carburetor".

The carburetor further consists of a spring 65 pressed air valve 5 which opens against the tension of a spring 6 by atmospheric pressure to permit the passage of air from the secondary air inlet tube to the induction passage of the carburetor. A fuel chamber 7 70 communicates by means of a passage 8 with the throat 9 of a primary inlet 10 having the form of a Venturi tube. The Venturi tube is projected laterally through a wall of the chamber 1 and extends to a point near the 75 center of the chamber where the thoroughly atomized fuel and air is delivered thereto. The opposite end of the tube is subjected to atmospheric pressure.

A spring pressed and normally closed fuel 80 valve 11 is provided in the fuel chamber 7 for controlling the passage of fuel from the chamber 7 to the passage 8. This valve is operated by a diaphragm 12, one side of which is subjected to atmospheric pressure. 85

As explained in the co-pending application referred to the passage of air through the primary air inlet or Venturi tube 10 creates a relatively high suction in the throat 9 due to the suction multiplying principles of the 90 Venturi tube. This suction is communicated to the fuel chamber below the diaphragm, causing the diaphragm to move through atmospheric pressure and open the valve 11, thus subjecting the fuel chamber 7 to the 95 throat suction of the Venturi tube. This suction is sufficiently high at all times during the normal operation of the carburetor to draw fuel from a supply tank 13 up into the fuel chamber 7 through a deliver tube 14.

A principal feature of my invention consists in a valve 15 disposed in the fuel passage 8 for restricting the flow of fuel to the throat 9 of the primary air passage 10 at all points below three-quarters to wide open throttle position. I refer here to the butterfly throttle 16 disposed in the passage of the carburetor and which is operated by movement of an arm 17 extending radially therefrom exteriorly of the carburetor. I thus cut down to a practical minimum, without sacrificing efficiency, the quantity of fuel admitted to the induction passage at all points below three-quarters throttle position.

The valve 15 has a stem 18 extending upwardly (see Figure 2) to a point adjacent to that end of the throttle shaft 19 remote from the arm 17. A cam 20 is carried on this portion of the shaft and secured thereto by screw 21 which falls off abruptly at 22 so as to permit a normally compressed spring 23 disposed beneath the valve to close the valve when the shaft is turned in the direction of the arrow 24 to a point below three-quarters open throttle position. The valve does not entirely close the passage 8 as I have provided a by-pass 25 through the valve which is sufficiently large to accommodate all of the fuel necessary for the efficient operation of the carburetor throughout the normal and low speed ranges.

As the suction multiplying property of the Venturi tube depends upon the quantity and velocity of air passing therethrough and not upon an obstruction in the delivery passage to the throat, I do not in anywise reduce the depression in the Venturi tube, below that necessary to operate the diaphragm against the spring pressed valve, though I do reduce the quantity of fuel that is admitted thereto through the openings 27 in the throat 9.

In order to clarify the illustration of the various parts of the carburetor I have shown, in Figure 1, the valve 15 and the throttle shaft as disposed in the same vertical plane as that of the Venturi tube 10. In practice, however, this valve should be in a plane out of that of the tube 10 so that there would be no possibility of its presence obstructing in any way the inlet orifice 30 of the venturi which, for efficient operation thereof, must be entirely exposed and accessible to atmospheric pressure.

It has been found that in carburetors of the fuel lift type which employ suction means embodied in the carburetor for lifting fuel that an accumulation of gas or air bubbles takes place in the fuel chamber, particularly, in such structure herein illustrated, beneath the diaphragm 12 which constitutes the uppermost part of the chamber. The presence of air in relatively large quantities causes at certain times the passage of the fuel through the delivery passage 8 in slugs with interposed air pockets. As a result of this pas-

sage of air in relatively large quantities, the carburetor functions so as to cause the engine to miss and operate erratically. To overcome this disadvantage I have provided two fuel passages for conducting fuel from the chamber 7 to the passage 8. The larger of the two, 28, communicates with the chamber 7 immediately beneath the diaphragm 12. The smaller passage 29 communicates with the chamber 7 at a point well beneath the top of the chamber so that no air bubbles may pass therethrough.

The passage 28 draws fuel and air bubbles as fast as they accumulate at the top of the fuel chamber into the passage 8, where they are comingled with a substantially solid fuel column admitted through the smaller passage 29. The result of the meeting of the streams from the passages 28 and 29 is such that the bubbles which enter through the passage 28 are quite thoroughly comingled with the composite fuel stream of both passages, and any large bubbles are broken up. This entirely precludes the presence of air in sufficient quantities at any time in the passage to cause erratic action of the engine.

In operation throughout the normal low speed ranges of the vehicle upon which the carburetor is used, the throttle 16 will remain below three-quarters open throttle position. The cam 20 during this time is disengaged from the upper end of the valve stem 18 so as to permit the valve 15 to remain closed by virtue of the compression spring 23, as shown in dotted lines in Figure 1.

In this manner the valve 15 permits the passage of fuel only through the by-pass 25 so that the quantity of fuel which may be drawn into the Venturi tube 10 and delivered into the induction passage is less than that available when the valve is open. The closed valve with by-pass does not in any way impair the fuel lifting properties of the Venturi tube so that there is no possibility of the suction created thereby falling below that degree necessary to lift fuel from the tank 13 into the chamber 7. When, however, the throttle 16 is open beyond three-quarters open position, the cam 20 moving with the shaft of the throttle valve engages with the stem 18 of the valve to open the valve to that position shown in full lines in Figures 1 and 2. This operation of the valve permits maximum flow of fuel to the Venturi tube 10 and in turn to the induction passage only when required for high speed or full load operation of the vehicle.

Air in the form of bubbles accumulated beneath the diaphragm 12 will be constantly withdrawn through the passage 28 into the passage 8 as fast as the bubbles are formed and rise to the top of the fuel chamber. This continuous exhausting of the fuel chamber of bubbles precludes all possibility of accumula-

tion of sufficient air to cause erratic engine operation.

In Figure 3 I have illustrated a modified form of the bubble eliminating structure in which I employ a threaded plug 32 having a relatively long narrow passage 33 therethrough which communicates at one end with the chamber 7 and beneath the upper level of the fuel and which corresponds in function to the passage 29, as described in the preferred form of the invention. The passage 28 in this embodiment is formed by a plurality of small passages 34, the function of which is to break up large bubbles into small bubbles as they pass into the passage 8. The fuel admitted through the passage 33 subsequently to the passage of the bubbles into the passage 8 is united with the comingled air and fuel to distribute and again divide the bubbles into smaller ones.

I claim:

1. The combination in a carburetor having a primary air inlet in the form of a Venturi tube, a passage for conducting fuel to the throat of the Venturi tube, a throttle valve for controlling the egress of fuel mixture from the carburetor, a normally closed valve having a by-pass interposed in the fuel passage and directly operated by the throttle valve to partially restrict the fuel passage at such times as the throttle valve is set for normal and low speed engine operation.

2. The combination in a carburetor of the fuel lift type having an induction chamber and a fuel nozzle, of a fuel chamber adapted normally to be filled with fuel, a passage connected at one end with the fuel nozzle and connecting at its opposite end through two passages with the fuel chamber, one of the passages being well beneath the level of fuel in the fuel chamber and the other at the uppermost part of the fuel chamber, said latter passage serving to conduct air bubbles from the fuel chamber into the fuel passage to the nozzle.

3. The combination in a carburetor having a primary air inlet in the form of a Venturi tube, a fuel chamber, a passage interconnecting the fuel chamber and the throat of the Venturi tube for drawing fuel from the chamber into the Venturi tube by the suction created upon the passage of air through the tube, a throttle valve controlling the egress of fuel mixture from the carburetor, and a valve interposed in the fuel passage and directly operated by the throttle valve, said valve comprising a valve seat, a valve head adapted to rest upon said seat at low engine speeds, and a by-pass for passing a limited amount of fuel when the valve head rests upon the valve seat to close the valve.

4. A carburetor having a fuel chamber, an outlet and a throttle valve controlling said outlet, and comprising in combination a Venturi tube forming a primary air inlet,

a fuel passage communicating with said fuel chamber for delivering fuel drawn therefrom into said Venturi tube by suction created by the passage of air therethrough, and a valve in said passage having an aperture therethrough restricting the fuel passage on closure of said valve and operable by said throttle valve to restrict said fuel passage at predetermined positions of the said throttle valve.

5. A carburetor having an induction chamber, a throttle valve disposed in said chamber, a means for maintaining a minimum depression in said chamber and comprising in combination a primary air inlet having the form of a Venturi tube, a fuel passage for conducting fuel to the throat of said tube, and a valve in said fuel passage restricting the flow of fuel through said passage when seated and operable by the throttle for permitting the free flow of fuel therethrough when said valve is unseated at predetermined positions of the throttle valve.

6. A fuel lift carburetor having a fuel chamber, an outlet and a throttle valve controlling said outlet, and comprising in combination a Venturi tube forming a primary air inlet, a fuel passage communicating with said fuel chamber for conducting fuel drawn therefrom into said Venturi tube by suction created by the passage of air therethrough, and a valve in said passage restricting the fuel passage in the closed position, and opened and closed by said throttle valve to restrict said passage and to permit the free flow of fuel therethrough at predetermined positions of said throttle valve.

7. A fuel lift carburetor, comprising in combination an induction chamber, a throttle valve therein, a primary air inlet having the form of a Venturi tube, a fuel passage for conducting fuel to the throat of said tube, and means for maintaining a minimum depression in said fuel passage including a valve in said fuel passage adapted when closed to supply fuel for normal and low speed ranges, said valve being closed by said throttle valve at predetermined positions thereof.

8. A fuel lift carburetor having an induction chamber and a fuel nozzle, and comprising the combination of a fuel chamber, a fuel passage communicating with said nozzle and an upper and lower connecting passage communicating with said fuel passage and said fuel chamber, said lower passage communicating with said fuel chamber below the fuel level and said upper passage communicating with the uppermost part of said fuel chamber to conduct air bubbles in said fuel chamber to said fuel passage and to co-mingle the air bubbles with the fuel drawn from said fuel chamber through the said lower fuel passage.

9. A fuel lift carburetor for drawing fuel

from a source of supply by suction, comprising a fuel chamber, a fuel nozzle for drawing fuel from said fuel chamber and a fuel passage communicating at one end with said nozzle and having a plurality of connecting passages at its opposite end communicating with said fuel chamber, a said connecting passage being restricted to provide a nozzle communicating with said chamber beneath the level of fuel therein, and the other said connecting passages communicating with said chamber above the fuel level.

10. A fuel lift carburetor for drawing fuel from a source of supply by suction, comprising in combination a fuel chamber for receiving fuel from the fuel source, a valve controlling the supply of fuel received by said chamber, a valve operating device in said fuel chamber, a fuel nozzle, and a fuel passage communicating at one end with said fuel nozzle and having a plurality of connecting passages at its opposite end communicating with said fuel chamber, said fuel nozzle providing suction through said passages in said fuel chamber opposing the closing of said valve by said valve operating device.

In witness whereof, I hereunto subscribe my name this 26th day of November, A. D. 30 1927.

ROBERT F. BRACKE.
